UNITED STATES PATENT OFFICE.

GEORGE A. BROWN, OF PITTSBURGH, PENNSYLVANIA.

FLUSHING-VALVE.

1,044,439.

Specification of Letters Patent. Patented Nov. 12, 1912.

Application filed March 8, 1911. Serial No. 613,097.

To all whom it may concern:

Be it known that I, GEORGE A. BROWN, a citizen of the United States, residing at Pittsburgh, Pennsylvania, have invented 5 certain new and useful Improvements in Flushing-Valves, of which the following is a specification.

My invention relates to valves and is herein illustrated as designed for flushing 10 water closets.

This invention is an improvement on the device of my Patent No. 913,097, of February 23, 1909, and its primary object is to provide against interference with the automatic 15 operation of the valve by manipulating the opening handle more than once.

Other objects are to improve the general operation as will be hereinafter described.

In the accompanying drawings Figure 1 20 is a vertical central section through the valve and casing; Fig. 2 is a horizontal section on line (II) in Fig. 1; and Fig. 3 is a similar section on line (III) of Fig. 1.

This form of valve is designed to operate 25 on high pressure lines without the use of storage tanks, and the valve is provided with air cushions to check its sudden movement in any direction. It is also automatic in operation except for the original tripping. Thus in Fig. 1 it will be seen that 30 the casing comprises an inlet chamber at 5 and an outlet at 6, which is connected with the water closet bowl or other vessel to be flushed.

The casing has an upward extension 7 35 which is closed by a cap having a downwardly projecting hollow guide stem 8 made nearly as large as the casing itself. On the stem 8 the main valve 9 fits neatly and the casing 40 is provided with two seats, 10 and 11, to receive the valve 9. The lower end of the valve is closed except for an opening 12 through which loosely passes the stem 13 having a relief valve 14, and being guided 45 in a spider 15, to reciprocate vertically. Loosely riding on stem 13 is a collar 16 attached by a link to the arm 17 mounted on shaft 18 of the operating handle 19. Also attached to sleeve 16 is a pivoted dog 50 20 which in its lower position rests on a lug 20^a, and engages in a notch 13^a in the stem 13. The raising of the collar 16 therefore carries upward the stem by engagement 55 of the dog 20 until the valve is completely opened by first lifting relief valve 14 against the tension of spring 21, and then raising

the main valve 9. The dog 20 eventually strikes the lug 27 and thereupon is released from the stem 13, after which it will be observed that no manipulation of the handle 60 will further disturb the action of the valve and its stem.

The main valve 9 is provided with inlaid gaskets 22 and 23 to engage the seats 11 and 10 respectively, and it is to be observed that it is almost as large as the casing surrounding it. The object of this is to prevent lifting the main valve by upward pressure as on flange 9^a, as soon as the pressure inside the valve is relieved through the opening 70 of 14. As the main valve rises it will drive out air and water through the passage 24 at the top of the hollow guide stem 8. This escapement is governed by the needle 25 in the cap, so that the rate of movement of 75 the main valve can be regulated. After the valve has risen, the water pressure on top passing up between the top of the main valve and the casing 7 will partly equalize the pressure under the valve and thereafter 80 by some of it passing in through the passage 24, the weight will cause the valve automatically to close. In closing, however, the valve cannot shut suddenly both because its lower seat will cut off the outlet (which is 85 larger than the inlet) and because any tendency to move downward faster than the water can enter at 24 will be resisted by the suction effect of the valve on its stem.

In the operation of the valve it is to be 90 noted that after it is opened, the chamber marked B will become partially empty because its outlet is greater than its inlet, and also that the chambers A and C will contain air and the inside of the valve will 95 also contain air. That is, in all of its movements the valve is subjected to an air cushion, and when it finally closes there will be an air cushion in chamber B to prevent water hammer. The advantages of having 100 the opening means engage the valve stem only at the proper position, will be obvious, since it prevents too much flushing and prevents interference with the valve's automatic movement.

Having thus described my invention and illustrated its use, what I claim as new and desire to secure by Letters Patent, is the following:

1. A water closet flushing valve provided 110 with a hand device for positively opening the valve, and means to release the valve

- therefrom after rising and to positively prevent reengagement with the valve until the valve returns to closed position.
2. The combination with a valve, of a device for positively opening it by hand, including a catch engaging the valve stem and means to prevent such engagement at any position except when the valve is closed, substantially as described.
10. 3. A high pressure flushing valve for water closets having means to retard its movement by fluid escapement, combined with a hand operated device to positively open the valve, and means to release the opening device only when the valve is entirely open and to reengage the valve only when it is entirely closed.
15. 4. The combination with a high pressure valve having a pilot release valve, of an operating handle for both valves and an engaging connection between the valves and a handle arranged to release only when the valve is at one limit of its travel, and positively prevented from reengagement until the valve returns to the other limit of its travel.
20. 25. In testimony whereof I have hereunto signed my name in the presence of the two subscribing witnesses.

GEO. A. BROWN.
